RAILWAY SIGNALING SYSTEM

Application filed December 18, 1928. Serial No. 326,724.

Our invention relates to railway signaling systems, and particularly to systems of the type involving direct current apparatus operated from a source of alternating current through the medium of rectifiers.

One object of our invention is the provision of a novel and improved system of this character having certain features which render it peculiarly safe and efficient.

We will describe one form of system embodying our invention, and will then point out the novel features thereof in claims.

The accompanying drawing is a diagrammatic view showing one form of signaling system embodying our invention.

Referring to the drawing, the reference characters 1 and 1^a designate the track rails of a railway along which traffic normally moves in the direction indicated by the arrows. These rails are divided by insulated joints 2 into a plurality of successive track sections, of which only two complete sections A—B and B—C, are shown in the drawing.

Each section is provided with means, hereinafter explained, for supplying the track rails with pulsating signaling current of normal or reverse polarity depending on traffic conditions in advance of the section.

Located at the entrance end of each section are two transformers T^R and T^N, the primary 3 of each of which is connected across the rails of the section. Interposed between one rail and the primary 3 of each transformer T^R is a rectifier 6^R, which permits current of reverse polarity, but not of normal polarity, to pass through the transformer primary. A similar rectifier 6^N is associated with each transformer T^N to permit current of normal polarity, but not of reverse, to pass through the primary of this transformer. The secondary 4 of each transformer T is connected with the input terminals of a full-wave rectifier F^R or F^N, and the secondary circuit of each transformer includes a condenser 7 for tuning the circuit to the frequency of the signaling current in the track rails. The transformers should have relatively large leakage resistance so that their secondary circuits may be sharply tuned. The output terminals of

each rectifier F^R are connected with the winding 8^R of a three position relay D, and the output terminals of each rectifier F^N are connected with the other winding 8^N of the same relay. The windings 8^R and 8^N of each relay D control an armature 9 in such manner that this armature is swung to the left when winding 8^R is energized, but is swung to the right when winding 8^N is energized, and occupies an intermediate position when both the windings are de-energized. The armature 9 of each relay D operates contact fingers 10 and 11 for purposes hereinafter explained.

Reverting now to the supply of current to the track rails, each section is provided with a line transformer designated by the reference character L with an exponent corresponding to the location. The primary 15 of each of these transformers is connected with a transmission line N, which is constantly supplied with alternating current from a generator K. Secondary 14 of each transformer L is connected with the track rails of the corresponding section, and a polarizing rectifier 12^N or 12^R is interposed in this connection in the following manner: Considering, for example, section A—B, when relay D^A for the section next in advance is de-energized, rectifier 12^R is interposed between

transformer secondary 14 and track rail 1. This rectifier permits the negative half of each alternating current wave to flow through the track rails, but prevents the positive half of each wave from reaching the rails. When relay D^A is energized in either the normal or the reverse direction, however, rectifier 12^N is interposed between the secondary 14 and track rail 1 in such manner as to permit the positive half of each wave to flow but to prevent the negative half of each wave from reaching the track rails. It follows that the rails of each section are supplied with pulsating current of reverse or normal polarity according as the section next in advance is occupied or unoccupied.

Located adjacent the entrance end of each section is a signal designated by the reference character S with an exponent corresponding to the location. As here shown, each signal comprises three electric lamps 103

G, Y and R, arranged when lighted to indicate respectively "proceed", "caution" and "stop". These lamps are controlled by contact 11 of the associated relay D in such manner that lamp G is lighted when the relay is energized in the normal direction, lamp Y is lighted when the relay is energized in the reverse direction, and lamp R is lighted when the relay is de-energized.

As shown in the drawing, the section to the left of point A is occupied by a car or train represented by an axle and a pair of wheels W, so that both windings 8^R and 8^N of relay D^A are de-energized, with the result that the armature and contacts of this relay occupy their intermediate positions. Lamp R of signal S^A is therefore lighted, so that this signal indicates stop. Contact 10 of relay D^A being in the intermediate position, polarizing rectifier 12^R is connected in the track circuit for section A—B, so that only negative half waves are supplied to this track circuit, with the result that winding 8^R of relay D^B is energized, and winding 8^N of relay D^B is de-energized. Relay D^B is accordingly energized in the reverse direction, so that its armature and contacts are swung to the left. Lamp Y of signal S^B therefore lighted, so that this signal indicates caution. Contact 10 of relay D^B being in its left-hand position, the normal polarizing rectifier 12^N is interposed in the track circuit for section B—C, so that winding 8^N of relay D^C is energized, and winding 8^R of this relay is de-energized. The armature and contacts of relay D^C are accordingly swung to the right, so that lamp G of signal S^C is lighted and the signal indicates proceed. Polarizing rectifier 12^N is included in the track circuit for the section to the right of point C, so that the signal for such section will indicate proceed.

The transformers and condensers associated with each relay D serve to absolutely prevent false operation of these relays by direct foreign current. Furthermore, the current which is used for the track circuits is coded in that every other half wave is eliminated, with the result that the system provides absolute protection against false operation of the track relays by alternating foreign current even when this current is of the same frequency as that of the signaling current; the reason for this is, that alternating current would energize both windings of each relay equally, and so would have no effect on the armature. Another feature of our invention is that the power required by the system is considerably less than that which is required for the operation of alternating current relays.

Although we have herein shown and described only one form of railway signaling system embodying our invention, it is understood that various changes and modifications may be made therein within the scope of the

appended claims without departing from the spirit and scope of our invention.

Having thus described our invention, what we claim is:

1. In combination, a section of railway track, means for supplying the rails of said section with pulsating current of normal or reverse polarity, two transformers the primaries of which are connected with the rails of said section, rectifiers associated with said primaries for permitting current of normal polarity but not of reverse to pass through one primary and for permitting current of reverse polarity but not of normal to pass through the other primary, two full wave rectifiers connected with the two secondaries respectively of said transformers, two relay windings supplied with current from said two full wave rectifiers respectively, and signaling means for said section controlled by said relay windings. 70 75 80 85

2. In combination, a section of railway track, means for supplying the rails of said section with pulsating current of normal or reverse polarity, two transformers the primaries of which are connected with the rails of said section, rectifiers associated with said primaries for permitting current of normal polarity but not of reverse to pass through one primary and for permitting current of reverse polarity but not of normal to pass through the other primary, two full wave rectifiers connected with the two secondaries respectively of said transformers, a condenser in the secondary circuit of each transformer for tuning such circuit at the frequency of the pulsating current in the track rails, two relay windings supplied with current from said two full wave rectifiers respectively, and signaling means for said section controlled by said relay windings. 90 95 100 105

3. In combination, a section of railway track, means for supplying the rails of said section with pulsating current of normal or reverse polarity, two transformers the primaries of which are connected with the rails of said section, rectifiers associated with said primaries for permitting current of normal polarity but not of reverse to pass through one primary and for permitting current of reverse polarity but not of normal to pass through the other primary, two full wave rectifiers connected with the two secondaries respectively of said transformers, a three position relay having two windings supplied with current from said two full wave rectifiers respectively whereby said relay is energized in normal or reverse direction according as the current in the track rails is of normal or reverse polarity, and signaling means for said section controlled by said relay. 110 115 120 125

4. A railway signaling system comprising a stretch of track divided into sections, two transformers for each section the primaries of which are connected with the rails of the

- section, rectifiers for each section for permitting current of normal polarity but not of reverse to pass through the primary of one associated transformer and for permitting current of reverse polarity but not of normal to pass through the primary of the other associated transformer, a full wave rectifier connected with the secondary of each transformer, a three position relay for each section having two windings separately supplied with current from the two full wave rectifiers associated with the section whereby said relay is energized in normal or reverse direction according as the current in the rails of the section is of normal or reverse polarity, a source of alternating current connected with the rails of each section, two polarizing rectifiers for each section, means operating when each relay is energized in either the normal or the reverse direction to interpose one of said polarizing rectifiers between said source and a track rail of the section next in the rear and thereby permit current of normal polarity but not of reverse to flow, means operating when each relay is de-energized to interpose the other polarizing rectifiers between said source and a track rail of the section next in the rear and thereby permit current of reverse polarity but not of normal to flow, and signaling means for said sections controlled by said rectifiers. 70
- 10 each section having two windings separately supplied with current from the two full wave rectifiers associated with the section whereby said relay is energized in normal or reverse direction according as the current in the rails of the section is of normal or reverse polarity, means controlled by the relay for each section for supplying the rails of the section next in the rear with pulsating current of normal polarity when the relay is energized in either the normal or reverse direction and with pulsating current of reverse polarity when the relay is de-energized, and signaling means for said sections controlled by said relays. 75
- 15 5. A railway signaling system comprising a stretch of track divided into sections, two transformers for each section the primaries of which are connected with the rails of the section, rectifiers for each section for permitting current of normal polarity but not of reverse to pass through the primary of one associated transformer and for permitting current of reverse polarity but not of normal to pass through the primary of the other associated transformer, a full wave rectifier connected with the secondary of each transformer, a three position relay for each section having two windings separately supplied with current from the two full wave rectifiers associated with the section whereby said relay is energized in normal or reverse direction according as the current in the rails of the section is of normal or reverse polarity, means controlled by the relay for each section for supplying the rails of the section next in the rear with pulsating current of normal polarity when the relay is energized in either the normal or reverse direction and with pulsating current of reverse polarity when the relay is de-energized, and signaling means for said sections controlled by said relays. 80
- 20 5. A railway signaling system comprising a stretch of track divided into sections, two transformers for each section the primaries of which are connected with the rails of the section, rectifiers for each section for permitting current of normal polarity but not of reverse to pass through the primary of one associated transformer and for permitting current of reverse polarity but not of normal to pass through the primary of the other associated transformer, a full wave rectifier connected with the secondary of each transformer, a three position relay for each section having two windings separately supplied with current from the two full wave rectifiers associated with the section whereby said relay is energized in normal or reverse direction according as the current in the rails of the section is of normal or reverse polarity, means controlled by the relay for each section for supplying the rails of the section next in the rear with pulsating current of normal polarity when the relay is energized in either the normal or reverse direction and with pulsating current of reverse polarity when the relay is de-energized, and signaling means for said sections controlled by said relays. 85
- 25 5. A railway signaling system comprising a stretch of track divided into sections, two transformers for each section the primaries of which are connected with the rails of the section, rectifiers for each section for permitting current of normal polarity but not of reverse to pass through the primary of one associated transformer and for permitting current of reverse polarity but not of normal to pass through the primary of the other associated transformer, a full wave rectifier connected with the secondary of each transformer, a three position relay for each section having two windings separately supplied with current from the two full wave rectifiers associated with the section whereby said relay is energized in normal or reverse direction according as the current in the rails of the section is of normal or reverse polarity, means controlled by the relay for each section for supplying the rails of the section next in the rear with pulsating current of normal polarity when the relay is energized in either the normal or reverse direction and with pulsating current of reverse polarity when the relay is de-energized, and signaling means for said sections controlled by said relays. 90
